UNITED STATES PATENT OFFICE.

JAMES C. MOORE, OF BROOKSTON, ASSIGNOR OF ONE-HALF TO TURPIE BROTHERS, OF MONON, INDIANA.

STEAM DITCHING APPARATUS.

SPECIFICATION forming part of Letters Patent No. 284,971, dated September 11, 1883.

Application filed May 13, 1882. (No model.)

To all whom it may concern:

Be it known that I, JAMES C. MOORE, a citizen of the United States, resident of Brookston, in the county of White and State of Indiana, have invented a new and valuable Improvement in Steam Ditching Apparatus; and I do hereby declare that the following is a full, clear, and exact description of the construction and operation of the same, reference 15 being had to the annexed drawings, making a part of this specification, and to the letters and figures of reference marked thereon.

Figure 1 of the drawings is a top or plan view of my ditching apparatus. Fig. 2 is a 15 side view of the same. Fig. 3 is a vertical sectional view of the same on the line xx , Fig. 1. Fig. 4 is a detail view, and Fig. 5 is a perspective view, of one of the scoops. Fig. 6 is a view of the scoop, bail, and prop-trip, the 20 scoop having been inverted or dumped.

This invention has relation to steam ditching-machines; and it consists in the construction and novel arrangement of the self-dumping and self-righting scoops connected to the 25 hauling-cables, the lever-bails and pendent prop-trips in connection with the scoops, the reversing-shaft, its clutch and sprocket-wheels, their bearing-slide, and the lever devices for moving the same, the slotted reversing-lever 30 and its weighted holding arms or checks, and the bearing-pulleys for the hauling-rope, all as hereinafter set forth.

In the accompanying drawings, the letter A designates a strong frame or support for the 35 operating-shafts and gearing. In bearings a on this frame is seated a power-shaft, B, which is designed to be connected with the driving-shaft of an engine by means of sprocket-wheels and a link-belt; or a link-belt may extend 40 from a sprocket-wheel on the engine-shaft to a sprocket-wheel, b, on the transverse driving-shaft C of this machine, which carries two sprocket-wheels, D and D'.

E represents the reversing-shaft, carrying 45 the loose sprocket-wheels F and F', which are connected to the sprocket-wheels D and D' by the link-belts G and G'. The link-belt G passes around both sprocket-wheels D and F, while the link-belt G' passes around the loose 50 sprocket-wheel F', under the sprocket-wheel

D', and around a small sprocket-wheel, D², secured in bearings D³, extending inwardly from the rear cross-beam of the frame A, as shown.

On the central portion of the shaft E, between the adjustable sprocket-wheels F, is secured a clutch-collar, H, and each sprocket-wheel FF' is formed with corresponding clutch-teeth on the inside face of its hub portion, to engage said clutch-collar. The outside hub portion of each of these sprocket-wheels FF' 55 is provided with a neck-bearing, c, which engages a bearing, d, at the end of an arm, K, which is attached to a bearing slide or transverse bar, L, seated loosely in guides e on the frame. By moving this slide-bar laterally 60 either sprocket-wheel F or F' can be brought into engagement with the clutch-collar H, so that the motion of the shaft E can be readily reversed while the driving-shaft C is turning continuously in the same direction, for the 65 reason that the sprocket-wheel F will be turned by its link-belt G, when in engagement with the clutch H, in the same direction as the sprocket-wheels D and D', while the sprocket-wheel F', having the intermediate sprocket-wheel, D', between it and the sprocket-wheel D², engaging only the upper line of the endless link-belt G', will be turned toward the 70 sprocket-wheel D' when the clutch H engages its clutch-teeth.

The movement of the transverse bearing-slide L is effected by means of a lever, N, which is pivoted to a bearing on the frame, and connected by a slot at its outer end to an arm, g, of the transverse horizontal lever P, which is 75 also pivoted to a bearing on the frame, as indicated at h. The inner end of the lever N works in a slot in the center of the bearing-slide L, as shown in dotted lines. By moving this lever P obliquely to the right or to the 80 left, one or the other of the sprocket-wheels F or F' is brought into engagement with the shaft E and governs its movement.

To the rear portion of the supporting-frame is pivoted a handle-lever, R, the arms of which 85 extend transversely and are connected to the slotted arms of the reversing-lever P by means of wires or rope connections k. The lever R is designed to enable the engineer to reverse 90 the movement of the scoops at will.

The scoops S are formed with side walls, l, and are provided with bails m, which are pivoted to the front portions of said side walls. These bails are levers, and each one has an extension or arm, n, which is connected to the hauling-chain r by a link or other suitable connecting device. The bail-lever m is provided with a pivoted arm or spur, p, constituting a pendent prop-trip of sufficient length to support the bail in an inclined and raised position when said prop-trip is resting by its lower end on the ground or on the top or bottom surface of the scoop, to dump and replace the scoop. The friction created by the contact of the scoop with the ground as the scoop is drawn either toward or from the machine is sufficient to afford a resistance that will enable the cable to dump or replace the scoop at will.

W W indicate channelled wheels on shafts V and on the reversing-shaft E, which are designed to engage and guide the cable-chain r through the machine, into and out of which the cable-chain passes through the slots s, which are formed in the arms of the reversing-lever P. By means of these slots s and stops t on the cable-chain r engaging the same when said chain is moving toward the machine, and the scoops have arrived at the ends of their respective paths, the lever P is moved sufficiently to operate the clutch-bearing slide L, and thereby to reverse automatically the movement of the hauling-chain.

When the scoops have become loaded in their progress through the soil, they can be dumped by simply reversing the movement of the hauling-cable. When this is done the action of the scoop in dumping is automatic, as the prop-trip engages its upper surface and holds the lever-bail in such position that its end is over the rear edge of the scoop. The reversed draft of the cable easily turns the scoop over. By again reversing the movement of the chain-cable the scoop is enabled to right itself, the pendent spur or trip engaging its bottom surface, and thus holding the lever-bail up and in rigid position, so that the draft of the chain cable acts to pull the scoop over into its normal position for work.

To the ends of the reversing-lever P flexible arms z are connected, said arms engaging bearings v, through which they slide, and carrying weights w on their ends, and serving as holding devices or checks to prevent the casual movement of the reversing-lever by the friction of the chain-cable.

Pulley-blocks Z Z are secured to strong posts or abutments at the farther end of the field or area to be ditched, opposite the machine, and through these pulley-blocks the endless hauling-cable passes.

Having described this invention, what I claim, and desire to secure by Letters Patent, is—

1. In a ditching-machine, the combination, 65 with a reversing-cable, of the self-dumping and self-righting scoops, provided with the lever-bails m and prop-trips p, substantially as specified.

2. In a ditching-machine, the scoop S, its 70 lever-bail m, and the pendent prop-trip p, pivoted to the lever-bail, substantially as specified.

3. In a ditching-machine, the slotted reversing-lever P, through which the cable 75 chain r passes, the stops t of the cable chain r, and the holding arms or checks z w, connected to said reversing-lever, substantially as specified.

4. In a ditching-machine, the combination, 80 with the slotted reversing-lever P, the hauling-cable r, and the reversing-shaft E, its clutch-collar H, and sprocket-wheels F F', of the bearing-slide L, connected to the lever P by the lever N and arm g, as shown, and the 85 wheels W, over which the hauling-cable passes through the machine, substantially as specified.

In testimony that I claim the above I have hereunto subscribed my name in the presence 90 of two witnesses.

JAMES C. MOORE.
